UNITED STATES PATENT OFFICE.

ELIHU THOMSON, OF SWAMPSMOTT, MASSACHUSETTS, ASSIGNOR TO
GENERAL ELECTRIC COMPANY, A CORPORATION OF NEW YORK.

NOZZLE FOR ELASTIC-FLUID TURBINES.

No. 799,809.

Specification of Letters Patent.

Patented Sept. 19, 1905.

Application filed March 6, 1905. Serial No. 248,874.

To all whom it may concern:

Be it known that I, ELIHU THOMSON, a citizen of the United States, residing at Swampscott, county of Essex, State of Massachusetts, have invented certain new and useful Improvements in Nozzles for Elastic-Fluid Turbines, of which the following is a specification.

Experience has demonstrated that under certain conditions eddies are formed in the fluid stream or streams as it or they flow through the nozzle or nozzles on their way to the wheel-buckets. These eddies are due to various causes and are in all cases objectionable, since they decrease the efficiency of the turbine. Other things being equal, these eddies seem to be more pronounced in those nozzles having shallow bowls or short discharge portions, or both, and in nozzles having large cross-sectional area.

20 The object of the present invention is to prevent objectionable eddying of the steam or other elastic fluid as it flows through the nozzles of a turbine or at least to so far prevent them that their effects may be disregarded.

25 In carrying out my invention one or more nozzles are employed, each nozzle preferably, but not necessarily, comprising a plurality of closely-associated fluid-discharging passages having the same angle of delivery, each passage having a supply chamber or bowl portion, a throat, and a discharge portion. Each nozzle or nozzle-section is arranged to convert a certain amount of the pressure of the 30 motive fluid into velocity and to discharge it at the proper angle against the wheel-buckets. It is preferable to have the nozzle-sections closely associated, since by so doing the fluid will be delivered in the form of a solid column 35 and the tendency for it to "spill" or spread out at the sides, considered in the direction of flow, will be reduced to a minimum. Instead of grouping the sections or passages together they may be separated, if desired. Each nozzle or nozzle-section is provided with one or 40 more partitions, which extend lengthwise through more or less of the supply chamber or bowl and into or through the throat into the discharge portion. These partitions are supported within the nozzle in any suitable manner, as by slotting the bowls or bowls and throats and inserting the edges of the partitions therein. The length of the partitions will ordinarily vary with different construc-

tions of nozzles, and they are generally more 55 useful in the stages of lower pressure, where the passages are large, than in the stages of high pressure, where the passages are small or relatively so. I do not wish to be understood, however, as limiting myself to any particular stage, since advantages will follow wherever they are used. In the low-pressure stages the bowls are relatively shallow and of relatively large diameter or area. This means that any tendency for the fluid therein or in 60 the stage discharging into the nozzles to create eddies by reason of its motion, especially in a direction more or less at right angles to the normal direction of flow in the nozzles, will have a greater effect on the fluid in the 65 nozzle-bowls than in those stages where the bowls are relatively small and deep. Where the nozzles or nozzle-sections are of relatively large cross-section, it is desirable to prevent 70 eddies in the flow of motive fluid in the discharge portion or that portion immediately preceding the entrance into the wheel-buckets. In some instances these partitions may be located within the nozzle itself, and in other 75 cases they may be carried by a separate support. These partitions, as well as those previously mentioned, should be arranged to direct the fluid particles as nearly as possible along parallel planes, since the fluid column will in this manner be rendered highly effective.

80 In the accompanying drawings, which illustrate one embodiment of my invention, Figure 1 is a partial section through the admission valves and nozzles of a multistage machine, showing means for preventing or largely reducing the eddying of motive fluid as it passes through the nozzles. Fig. 2 is a section of a nozzle adapted to be located between 85 stages and showing means for preventing eddying of the motive fluid at the throat and also at the discharge portion. Fig. 3 is a similar view with a slightly-different arrangement of partitions. Fig. 4 is a sectional view of the low-pressure nozzles of a multistage 90 turbine, having partitions at the throats for preventing eddying of the fluid and other partitions located at the end of the nozzle-sections for the same purpose.

1 represents the casing of the turbine, containing one or more stages, each stage having one or more rows of wheel-buckets 2 of suitable shape. Where more than a sin-

gle row of wheel-buckets are provided for each stage, a row of intermediate buckets 3 is provided between each two rows of wheel-buckets. These intermediate buckets may 5 extend wholly or partially around the wheel, as desired. Mounted on the casing and extending through an opening therein is a nozzle 4, comprising a plurality of fluid-discharging passages, each passage having a throat 5, 10 a bowl or supply-chamber 6, and an expanding discharge portion 7. The admission of fluid to the nozzles is controlled by one or more valves 8 in response to changes in speed. In the present instance each nozzle-section is 15 provided with its own valve, and the valves are arranged to be operated successively to increase or decrease the admission of steam or other elastic fluid to the buckets by changing the width of the fluid column. The valves 20 are located within a suitable chest 9, through which the stems of the valves extend. Mounted within the bowl and extending into the fluid-discharging passages are partitions 10. In the left-hand passage a single partition is 25 shown, while in the right-hand passage two partitions are shown. The number can be increased, if desired. The number will depend chiefly upon the cross-sectional area of the throat of the passage. These partitions 30 may be supported in slots formed in the walls of the passage, which receive the edges of the partitions. In this figure the partitions extend from the bowl through the throat and into the discharge portion of the passage or 35 nozzle-section. In Fig. 4 these partitions terminate at or about the beginning of the throat 5. They extend, however, far enough back into the bowl to prevent eddying at this point.

40 In Fig. 2 two partitions 10 are shown extending from the bowl through the throat into the discharge portion. These partitions are spread apart somewhat at their receiving end to more effectively receive and direct the 45 passage of motive fluid. The discharge portion of the nozzle is provided with one or more partitions 11, which assist in directing the motive fluid as it passes to the wheels.

In Fig. 3 the left-hand section is provided 50 with a single partition 10 at the throat and two partitions 11 at the discharge end. In the right-hand section two partitions 10 are shown in the throat-passage, the discharge-passage being without them.

55 In Fig. 4 is shown a plurality of parallel partitions 12, which are mounted upon a common support 13. This support is for the purpose of manufacturing made separate from the nozzle structure. These partitions being 60 parallel and of suitable length serve to direct the motive fluid at the proper angle against the wheel-buckets 2 and at the same time prevent objectionable eddying at this point. These partitions should be made as thin as 65 possible, and it is preferable to place them

fairly close together, since they will more effectively direct the fluid particles as they pass to the wheel. In this figure some of the partitions register with the sharpened ends of the walls separating the passages; but they 70 may be so arranged that the ends are located between two partitions.

The nozzles shown are of the expanding type; but the invention is applicable to nozzles, sectionalized or not, which are non-expanding in character.

In accordance with the provisions of the patent statutes I have described the principle of operation of my invention, together with the apparatus which I now consider to present the best embodiment thereof; but I desire to have it understood that the apparatus shown is only illustrative and that the invention can be carried out in other ways.

What I claim as new, and desire to secure 85 by Letters Patent of the United States, is—

1. A nozzle for elastic-fluid turbines, comprising a supply chamber or bowl, a throat receiving fluid from the chamber or bowl, a discharge portion communicating with the 90 throat, and means for preventing the eddying of motive fluid as it passes through the supply chamber or bowl.

2. A nozzle for elastic-fluid turbines, comprising a supply chamber or bowl, a throat receiving fluid from the chamber or bowl, a discharge portion communicating with the throat, and a partition located in the chamber or bowl, which extends into the throat and prevents the eddying of the motive fluid in 100 the bowl and throat.

3. A nozzle for elastic-fluid turbines, comprising a bowl, a contracted throat opening into the bowl, a discharge portion communicating with the throat and co-operating therewith to impart velocity to the motive fluid, and one or more partitions which extend from the bowl through the throat into the discharge portion to prevent eddying of the motive fluid as it passes through the nozzle. 105

4. A nozzle for an elastic-fluid turbine, comprising a plurality of closely-associated fluid-discharging passages having the same angle of delivery, such passages being brought close together at their discharge ends so that the 115 fluid will issue as an unbroken column, and partitions which subdivide the passages at their inlet ends and prevent eddying of the motive fluid in a direction contra to the direction of flow.

5. A nozzle for elastic-fluid turbines, comprising a discharge-passage, a partition for preventing eddying of the motive fluid at the inlet end of the passage, and a partition separated from the first which directs the 125 discharge of fluid and also prevents eddying.

6. A nozzle for elastic-fluid turbines, comprising a discharge-passage, a partition for preventing eddying of the motive fluid at the inlet end of the passage, and a plurality of 130

parallel partitions which are located at the end of the discharge portion and direct the fluid particles flowing to the wheel-buckets and prevent eddying.

5 7. A nozzle for elastic-fluid turbines, comprising a bowl and a discharge portion, and one or more partitions extending in the direction of flow of the motive fluid which pre-

vent the eddying of the fluid as it passes through the bowl.

In witness whereof I have hereunto set my hand this 3d day of March, 1905.

ELIHU THOMSON.
